UNITED STATES PATENT OFFICE.

GEORGE OTIS DRAPER AND CLARENCE E. METCALF, OF HOPEDALE,
MASSACHUSETTS, ASSIGNORS TO DRAPER COMPANY, OF HOPE-
DALE, MASSACHUSETTS, A CORPORATION OF MAINE.

ROTARY RING-SPINNING APPARATUS.

No. 820,628.

Specification of Letters Patent.

Patented May 15, 1906.

Application filed August 26, 1905. Serial No. 275,857.

To all whom it may concern:

Be it known that we, GEORGE OTIS DRAPER and CLARENCE E. METCALF, citizens of the United States, and residents of Hopedale, county of Worcester, State of Massachusetts, have invented an Improvement in 5 Rotary Ring-Spinning Apparatus, of which the following description, in connection with the accompanying drawings, is a specification, like numerals on the drawings representing like parts.

This invention relates to spinning and twisting apparatus, and more particularly to that type wherein rotary rings are employed; 15 and it has for its object the production of novel and efficient means for sustaining and guiding the rotary ring and for limiting the axial and radial movements thereof.

The various novel features of our invention 20 will be fully described in the subjoined specification, and particularly pointed out in the following claims.

Figure 1 is a front elevation of a rotary ring and the coöperating parts embodying 25 one form of our invention. Fig. 2 is a top plan view thereof, and Fig. 3 is an enlarged diametral section on the line 3-3, Fig. 2, the downhold of the ring-carrier being broken out to show some of the structure beyond it.

30 The spinning or twisting ring 1 is herein shown as of the double-flanged reversible type, the upper flanges 2 constituting a race-way for the traveler 3 and the lower flanges 4 resting in an annular seat 5 in the ring-carrier. In practice this seat is of such size that 35 the lower flange of the ring can be forced therewith and held by frictional engagement, so that the ring and carrier rotate as a unit.

We have herein shown the ring-carrier as a 40 metallic ring or annulus 6, having a thin depending circular extension or downhold 7, provided with an external lateral lip 8 and vertically slotted at 9, (see Fig. 3,) the slotting of the downhold and the thinness of the

45 same permitting it to be slightly compressed when applied to the casing or guide to be described. The ring-carrier has an outer down-turned flange 10, connected by a thin web 11, and the under side of the carrier between 50 downhold and flange is shaped to form a transversely-convex annular bearing 12, as shown in Fig. 3, there being a considerable

clearance between the bearing and the flange, as shown.

A holding-plate 13 is suitably secured to 55 the ring-rail 14 in any suitable manner, as by screws 15, Fig. 2, the plate having upturned ears 16, between which is snapped the outer flange 17 of the casing 18. The casing is cylindrical in shape, and it has an internal 60 flange 19 to project over the lip 8 of the downhold, there being a clearance between to permit a limited vertical or axial movement of the ring-carrier. The flanges 17 and 19 form a flat base for the casing, whereby it is 65 firmly supported on the holding-plate 13, and when the parts are assembled the downhold is pushed down into the casing and compressed until the lip 8 snaps past the flange 19, the lip being preferably rounded to facilitate 70 such assembling.

As will be seen by an inspection of Fig. 3, the ring-carrier can move radially to a limited extent, owing to the clearance between the flange 19 and the exterior of the downhold; but such movement is limited to that requisite for the proper freedom of the ring-carrier. The upper end of the casing is beveled at 20 to form an inverted conical seat 75 for the bearing 12 on the ring-carrier and 80 tangential thereto, such seat coöperating with the bearing to vertically sustain the ring-carrier, while permitting some tipping motion thereof. When the ring and ring-carrier are in full rotation, the bearing will in 85 practice rise from the seat in a manner well known in rotary-ring-spinning apparatus. Between the casing and the flange 10 of the ring-carrier we interpose a contact member, shown as a ring 21, loosely embracing the 90 casing and vertically supported by the flange 17 thereof. It is found in actual practice that the interposition of a loose contact member between the casing and a part of the ring-carrier makes the ring run in a very 95 much smoother manner.

From the foregoing description, in connection with the drawings, it will be seen that we have provided for limiting the axial and radial movement of the ring and its connected carrier and also for a tipping movement thereof, while permitting the desired rotary motion of the ring during the spinning operation.

Having fully described our invention, what we claim as new, and desire to secure by Letters Patent, is—

1. The combination with a rotary spinning-ring having a downturned flange and a concentric depending, annular downhold provided with a lateral lip, of a fixed cylindrical casing to vertically sustain the ring, an inturned flange on the casing to coöperate with the lip of the downhold and limit axial movement of the ring, and an annular contact member loosely interposed between the casing and the downturned flange.
2. The combination with a rotary spinning-ring having an annular, transversely-convex bearing, of a casing having a beveled seat to coöperate therewith and sustain the ring vertically, means to limit axial movement of the ring, and an annular contact member loosely surrounding the casing and interposed between it and an adjacent portion of the ring.
3. The combination with a rotary ring having an outer downturned flange and an inner depending downhold provided with a lateral lip, of a fixed annular casing between said flange and downhold, an inturned flange on the casing to coöperate with the lip and limit axial movement of the ring-carrier, and an annular contact member loosely interposed between the casing and the downturned flange on the ring-carrier.
4. The combination with a rotary ring having an outer downturned flange and an inner depending downhold provided with a lateral lip, of a fixed annular casing between said flange and downhold, inner and outer flanges on the casing, the former coöoperating with the lip to limit axial movement of the ring, and a contact-ring loosely surrounding the casing between it and the flange of the ring and vertically sustained by the outer flange on the casing.
5. The combination, with a spinning-ring, of a detachably-connected ring-carrier having an outer downturned flange and an inner, depending annular downhold, a fixed cylindrical casing having at its top a seat to vertically sustain the ring-carrier, and a contact-ring loosely interposed between the flange of the ring-carrier and the casing.
6. The combination, with a spinning-ring, of an attached rotary ring-carrier having an annular, transversely-convex bearing and a downturned concentric flange, a fixed annular casing having a beveled seat to coöperate with the bearing, and a contact member rotatably mounted on the casing and loosely interposed between it and said flange.
7. The combination, with a spinning-ring, of an attached rotary ring-carrier having an

annular, transversely-convex bearing and a downturned concentric flange, a fixed annular casing having an inverted conical seat for the bearing and to permit slight tipping of the ring-carrier, means, including a compressible member on the latter, to limit axial movement of the ring-carrier, and a rotatable contact-ring loosely interposed between the casing and the flange on the ring-carrier.

8. The combination with a spinning-ring, of an attached rotary ring-carrier, a fixed casing to vertically support the ring-carrier, means to limit axial movement thereof, and means, including a contact-ring loosely surrounding the casing and coöperating with the ring-carrier, to limit radial movement thereof.

9. In ring-spinning apparatus, in combination, a ring, a rotary carrier therefor having a downturned outer flange, a fixed annular casing to vertically sustain the ring-carrier, and a contact member loosely interposed between the casing and the flange, to limit radial movement of the ring-carrier.

10. The combination with a rotary ring-carrier having a depending, slotted downhold provided with a lateral lip, and a downturned annular flange, of a fixed cylindrical casing adapted to engage and vertically sustain the ring-carrier between the downhold and flange, and an internal flange on the casing to overlap the lip of the downhold.

11. The combination, with a spinning-ring, of an attached rotary ring-carrier having an annular, transversely-convex bearing and a downturned, concentric flange, a fixed annular casing having a beveled seat to coöperate with the bearing, and a contact member loosely mounted on the casing between it and said flange.

12. The combination with a rotary spinning-ring provided with an annular, transversely-convex bearing, of a casing having a seat to coöperate tangentially with the bearing and sustain the ring vertically, coöperating devices on the casing and movable with the ring, respectively, to limit axial movement of the latter, and an annular contact member loosely surrounding the casing and between it and an adjacent portion of the ring.

In testimony whereof we have signed our names to this specification in the presence of two subscribing witnesses.
